UNITED STATES PATENT OFFICE.

HERMAN C. STERN, OF WAUKESHA, WISCONSIN.

ASH-SIFTER.

1,308,963.

Specification of Letters Patent.

Patented July 8, 1919.

Application filed January 20, 1919. Serial No. 272,069.

To all whom it may concern:

Be it known that I, HERMAN C. STERN, a citizen of United States, residing at Waukesha, in the county of Waukesha, State of Wisconsin, have invented certain new and useful Improvements in Ash-Sifters; and I do hereby declare the following to be a full, clear, and exact description of the invention, such as will enable others skilled in the art 10 to which it appertains to make and use the same.

Heretofore, in the class of ash sifters, various actuating devices have been provided, but irrespective thereof, the construction of 15 the device was such that whether the sifter was of the rotary or reciprocating type or had other form of agitating means, the issuance of dust could not be prevented and the depositing of ashes to be sifted, as well as 20 the discharge of the cinders and the emptying of the siftings or screenings could only be accomplished with difficulty.

It is therefore an object of my invention to provide an ash sifter so-constructed as to 25 possess improvements not only in facilitating the operations above set forth, but also to improve and simplify the construction thereof, by providing a support in which is hung in a novel manner, a container, adapted through the medium of novel means, to 30 be agitated or have imparted thereto, a reciprocating oscillatory motion, for separating the dust and finer particles from the coals and larger particles or cinders, as well 35 as to facilitate the depositing of the ashes for the sifting operating and the sifting thereof with the least possible escape of dust, both during the agitation of the sifter and in emptying or discharging the cinders 40 and the dust.

The invention further comprehends an improved ash sifter embodying a container suspended by a series of hangers and adapted to be agitated with an oscillatory reciprocating motion by means of a handle or lever supported by the carrying frame, the container having hinged thereto, a screen in the form of a tray provided with a sliding cover permitting the depositing of the ashes 45 to be sifted but serving to prevent the escape of dust during and after the sifting operation, as well as a removable pan for receiving the dust or screenings, while a fastener is provided to serve the double function of

holding the hinged tray of the screen toward 55 the container and also to hold the pan in a closed position.

With the above objects and others in view, as will appear as this specification proceeds, the invention comprises certain novel combinations and arrangements of parts to be hereinafter set forth in detail and claimed.

Reference is had to the accompanying drawings forming a part of this application and wherein like reference characters represent corresponding parts throughout the several views in which:

Figure 1 is a side elevation of my improved ash sifter.

Fig. 2 is an end elevation thereof.

Fig. 3 is a similar view of the opposite end.

Fig. 4 is a longitudinal sectional view, vertically of the sifter, and

Fig. 5 is a transverse vertical sectional view of the device.

As shown in the accompanying drawings, my improved ash sifter comprises a supporting frame generally indicated by the reference character F, which frame is made up of a pair of spaced side portions or supports 80 10, connected by a cross brace 11, holding the side members of the frame in rigid spaced parallel relation. The side members or plates are preferably enlarged toward 85 their base portions so as to give a good supporting effect.

Arranged and supported between the side members of the frame is a container 12 made up of a lower or base portion B, which is in 90 the form of a substantially rectangular receptacle having a bottom portion 13, sides 14 and an inclined end wall 15, the opposite end of the container being freely open. This container is suspended between the side members of the supporting frame through the medium of a series of hangers 16 of double crank-like formation, having the crank portions thereof journaled in the respective side members of the frame near the top edges thereof and also in the side walls 14 of the container, either directly or through the medium of suitable bearings as it will no doubt be understood, will form a common expedient for this purpose.

By this means, it will be seen that the container will be supported or suspended between the side members of the frame to have

imparted thereto, an oscillatory reciprocating motion for the purpose of agitating the ashes to separate the dust and finer particles from the coals and larger particles of the cinders, as it is thought will be comprehended. For this purpose there is pivoted to one of the side members of the frame, a handle or lever 17 which has connection with the container through the medium of a connecting rod 18, also in the form of a double-ended crank. As will be seen from an inspection of the drawings, the hangers 16 are arranged in pairs at opposite sides of the sifter and the connecting rod is disposed intermediately of the hangers at one side so that by oscillating the lever, movement will be imparted to the container for agitating the same as heretofore set forth.

The container is designed to carry the screening mechanism and for this purpose, the upper longitudinal edges of the side portions of the container are rabbeted at their inner sides as shown at 18' to provide guideways for the reception of a screen tray T forming part of the ash sifter. This tray is in the form of an open rectangular tray or frame, the side portions 19 of which have their lower edges rabbeted at the outside to interfit the guideways produced by the rabbeted upper edges of the base portion of the container, so as to produce a dust-proof joint. This joint also facilitates the replacement of the screen tray upon the container, when said tray is shifted from a position to discharge the contents thereof, to a position upon the container, for the sifting operation.

The tray is provided with a wire mesh bottom 20 serving the function of a screen or sieve and with an inclined end wall 21 arranged for disposition above the inclined end wall 15 of the container, the abutting edges of these walls being hinged together as shown at 22, so as to permit the tray to be tilted from a position of rest supported horizontally upon the container at the upper edges thereof in the manner specified, to a rearwardly inclined position for discharging the cinders.

The container is designed to receive a pan 23 which is slidably received within the open end of the container, the inner end wall 24 of the pan being inclined in conformity with the adjacent end wall of the container when the pan is in position, while the outer end wall 25 extends outwardly to abut the edges of the side walls and bottom of the container as an additional means of producing an effective seal against the escape of dust and ashes, so desirable in a device of this character. The tray T is provided with an end wall 26 disposed above the end wall 25 and the side walls 19 are provided with grooves 27 in the inner faces thereof to receive a sliding cover 28 which projects over the end

wall 26 to form an additional seal against the escape of dust. Locking means is also provided to serve the double function of holding the hinged tray toward the container and in sealing engagement therewith during the sifting operation, as well as to secure the pan in a receiving position as illustrated may consist of a hook 29 designed to engage a stud 30 projecting from the wall 25 of the pan. In this manner 75 when the sifting operation has been completed, the tray can be tilted to discharge the coals and cinders retained therein and the pan can be removed to discharge or empty the dust and finer particles which 80 have sifted through the screen. It is important in accomplishing the objects sought, that the sliding cover 28 may be drawn as far as desired so as to uncover only the bottom portion of the tray during the discharging thereof, so that the dust will be prevented from arising and scattering over the operator, while the relation of the parts is such as to prevent the escape of the dust particles during the sifting operation, but 85 in permitting same to settle before emptying the pan of its contents. Thus the objects mentioned have been accomplished in an effective manner and with a device possessing a considerable number of points of advantage in simplicity of construction and operation, as well as from a commercial point of view as relates to its possibilities of manufacture and production for sale.

Having thus described my invention, what 100 I claim and desire to secure by Letters Patent of the United States is:—

1. An ash sifter comprising a container, a supporting frame for said container, hangers supporting the container within said frame for oscillatory reciprocating movement, a lever carried by the frame and connected to the container for imparting movement thereto as aforesaid, an ash tray hinged upon the container and provided with a cover and a sifter bottom, a pan in the container beneath the tray and fastening means between the tray and pan to serve the two-fold purpose of securing the tray toward the container and the pan in position. 115

2. In an ash sifter, a supporting frame, a container suspended therein for agitation, means for agitating the container, said container being closed at one end and open 120 at the other end a pan slideable into and out of said open end a sifting tray hinged to the opposite end of the container and forming a removable cover and a catch at the opposite end of the pan and tray to simultaneously hold both in closed operative positions or permit opening and tilting thereof, respectively, as and for the purposes specified. 125

3. The combination with a supporting 130

frame; of a container supported therein for reciprocating oscillatory movement and comprising a bottom section and a top section having a wire mesh bottom, means to 5 permit dumping of the top section, a pan beneath said top section and means to connect said pan and top section to hold the same in position or permit displacement thereof relative to each other and the container.

4. The combination with a supporting frame; of a container supported therein for reciprocating oscillatory movement and comprising a bottom section and a top section 15 having a wire mesh bottom, said container having an inclined end, said top section being hinged to the bottom section at said end to permit raising of the top section for discharging the contents thereof, a 20 slidable cover for the top section, the opposite end of the bottom section of the container being open and the adjacent end of the top section closed, a tray fitting the bottom section and closing said open end 25 thereof and a catch for holding the top section in lowered operative position.

5. An ash sifter comprising a container, a supporting frame for said container, said supporting frame comprising side members and connections therebetween, crank hangers carried by the sides of the frame and suspending the container within the frame for oscillatory reciprocating movement and a lever carried by the frame and having a

crank connection with the container for imparting movement thereto.

6. An ash sifter including a container, a pan 50 slidable into one end of the container, a sifting tray at the top of the container and means for connection between the pan and tray at one end of the container to hold the same in operative relation or to permit simultaneous or independent displacement thereof.

7. An ash sifter including a container, a 45 pan slidable into one end of the container, a sifting tray hinged to the opposite end of the container, a cover for said tray adapted to be opened from the hinged end thereof, by an operator at the opposite end, 50 from which the pan is adapted to be drawn from the container and a detachable connection between the pan and tray at the latter end of the container whereby an operator can connect the two in operative relation for sifting or disconnect the two whereby the cover for the tray can be opened and the tray raised to discharge the contents thereof at the end opposite the operator or the tray lowered and its cover closed, and 55 the pan displaced for discharging the contents thereof or replaced, as desired.

In testimony whereof, I affix my signature, in the presence of two witnesses.

HERMAN C. STERN.
